United States Patent Office

Des. 178,523
Patented Aug. 14, 1956

178,523

TOY ROBOT FIGURE

Nicholas V. Lackovic, Pittsburgh, Pa., assignor to Wolverine Supply and Manufacturing Company, Pittsburgh, Pa., a corporation of Pennsylvania

Application October 12, 1955, Serial No. 38,335

Term of patent 14 years

(Cl. D34—4)

Fig. 3

Fig. 1

Fig. 2

Fig. 1 is a front elevational view of a toy robot figure showing my new design;

Fig. 2 is a side elevational view thereof; and

Fig. 3 is a top plan view.

I claim:

The ornamental design for a toy robot figure, as shown.
